GROUND ANCHOR OR DEADMAN

Lloyd M. Blanchard, Girard, Kans.

Application July 21, 1941, Serial No. 403,294

4 Claims. (Cl. 189—92)

This invention relates to ground anchors for guy wires or similar equipment, and has for its general object to produce a device of this kind which can be withdrawn from a bore hole after use without the necessity for excavating to recover the tool. One of the chief objects of the invention is to provide a tubular casing closed at its opposite ends and having a slotted wall, whereby a housing is formed from which the ground engaging flukes may be projected, and into which the flukes can be withdrawn, leaving no projections to interfere with the removal of the tool by pulling it out of a bore hole.

Another object of the invention is to provide a totally enclosed structure of the general nature described, in which the operating parts are protected or housed from contact with the earth which might collect or wedge behind the flukes and interfere with the withdrawal thereof when it was desired to contract the device.

Another object of the invention is to produce a construction in which the load, on the forcing of the flukes into the earth, is not carried by the hinge pins of the flukes, but is transmitted through a heel formed on the pivoted end of each of the flukes.

A further object of the invention is to produce a construction of the general nature indicated above, provided with a sectional rod to extend from the tool to the ground surface, whereby the tool can be sunk to any desired depth, and the guy wire receiving rod may be lengthened or shortened as necessary in accordance with the depth and angle of the bore hole.

With the general objects named in view and others as will hereinafter appear, the invention consists in certain novel and useful features of construction and organization of parts as hereinafter described and claimed; and in order that it may be fully understood, reference is to be had to the accompanying drawings, in which:

Figure 1 is a central longitudinal section of an anchor embodying the invention as it will appear when positioned within a bore hole, a pair of opposite flukes being shown in side elevation in retracted position, and being shown in dotted lines in projected position.

Figure 2 is an enlarged side elevation of the anchor as it may appear as the flukes start to project.

Figure 3 is a cross section on the line III—III of Figure 1, but on the same scale as Figure 2.

Figure 4 is a cross section on the line IV—IV of Figure 2.

Figure 5 is an inverted plan view of the anchor with the flukes expanded to their full extent.

Figure 6 is an enlarged perspective view of one of the flukes.

Figure 7 is an inner face view of one of the flukes.

In the said drawings, where like reference characters identify corresponding parts in all of the figures, 1 is a tubular casing or shell closed at its lower end by a plug 2 having a curved conical guide face 3 within the casing, and a convex bottom outer face 4 having a transverse projecting fin or web 5 to be embedded in the ground at the bottom of a bore hole. This fin 5 establishes a resistance point to prevent rotation of the casing 1 in the bore hole, until the flukes (hereinafter identified) have been expanded to bite into the earth. The upper end of the cylinder 1 may be screw threaded and locked by a set screw 1a as shown, or may be otherwise attached, to a solid head 6 of more or less conical form. The head 6 is formed with a passageway rotatably receiving a rod 7, which has its lower end stepped as at 8 in a socket 9 in the bottom of plug 2 to constitute a journal support. In order that the load may be placed on the head 6 in withdrawing the device from a bore hole, the head is formed with a large socket 10 receiving an enlarged shoulder bearing portion 11 formed on the rod 7. The bearing portion 11 is locked in the socket by a screw threaded plug 12, held secure by a set screw 12a, or the rod 7 may be secured in some other suitable way.

The casing 1 is provided with a series of spaced longitudinally extending slots 13 (four being shown in the drawings). Threaded on the rod, within the casing, is a nut 14, provided with a series of rounded heel ends 15a of a series of flukes 15 which are pivoted to the nut on pins 16. The outer surfaces 15b of the rear ends of the flukes are tangential to their heels 15a and are curved transversely to fit within the cylinder chamber as will hereinafter appear. The pivotal relation is such that the nut 14 and the heels of the flukes take the full load during the expansion of the flukes, the pins bearing only the light load of contracting or withdrawing the flukes into the housing.

Each of the pivoted flukes 15 is, by preference, of T-shape in cross section. The slots 13 are shorter than the flukes so that when the nut 14 is withdrawn until it abuts the head 6, the pivoted ends of the flukes are drawn into the non-slotted upper end of the casing 1, and the latter, by guiding contact with the outer sides

of the heels of the flukes, locks the flukes parallel to the rod 1 and holds them against outward swinging movement on their pivot pins 16.

The opposite or ground engaging ends of the flukes 15 are formed with curved surfaces 17 for engagement with conical guide or deflecting surfaces 3 of the plug 2 so that the flukes will be expanded outwardly into the soil as the nut 14 travels downwardly when the rod 1 is rotated in the proper direction. When the flukes 15 are to be retracted, it will be clear that reverse turning of rod 1 will cause the nut 14 to travel more or less freely upwardly without appreciable resistance through contact of the flukes with any part of the casing, until the nut has passed some distance into the chamber at the upper unslotted end of the casing, at which time contact of the end of the slots 13 with the backs of the flukes, will for the first time exert a load tending to swing the flukes back into the casing. This particular construction is of essential advantage since it greatly increases the leverage tending to close the flukes, and thus avoids undue stress on the pivot pins 16. With the construction shown, it will be evident that the operating parts are substantially protected against earth contact should the bore hole above the tool cave in before it is time to pull the tool for transfer to a new location.

It will also be apparent that although the rod 1 may be made sufficiently long to extend to the surface of the ground to receive the end of a guy wire or other instrumentality, the preferred construction is to provide an extensible rod so that bore holes of varying depth may be readily accommodated. For this purpose, the rod 1 terminates just beyond the head of the casing in a cross groove 18. A series of intermediate sectional rods 20 of suitable length (one only appearing) having their opposite ends respectively terminating in male and female connections, such as tongues 21 and grooves 22, are provided, the final section of the assembly being an eye bolt section 23 having a tongue on its lower end. The interlocking ends of the sections are each provided with threaded portions 24, and when the rod has been assembled, the interlocked ends are screw threaded into enclosing sleeves 25 to lock the parts together. With this construction it will be evident that the rod in effect becomes one piece so that it may be safely rotated in either direction, as well as hold an axial load or pull.

From the above description, it will be apparent that I have produced a construction which embodies all of the features of advantage set forth as desirable, and while I have described and illustrated the preferred embodiment it is to be understood that I reserve the right to all changes within the spirit and scope of the appended claims.

I claim:

1. An expanding guy anchor comprising a rod provided at one end with means for securing a guy wire, a tubular casing axially receiving one end of the rod and fixed thereto against longitudinal movement, said casing being formed with a series of spaced slots, a portion of the rod within the casing being threaded, a nut within the casing threaded on the rod, and a series of flukes hinged to the nut and moving in and out of the slots in the casing in response to movement of the nut, the backs of the flukes substantially coinciding with and closing the casing slots when the flukes are in retracted position.

2. An expanding guy anchor comprising a cylindrical casing closed at its opposite ends by a plug and a head, a socket in said head and a bearing in the plug, a threaded rod rotatably extending through the head and having its lower end journaled in the plug bearing, a circumferential shoulder on the rod journaled in the head socket and locked therein against movement longitudinally thereof, a series of spaced slots in the wall of the casing, a travelling nut threaded on said rod, and a series of flukes hinged to the nut and having guide surfaces in contact with the casing to project and withdraw the flukes on longitudinal travel of the nut.

3. An expanding guy anchor comprising a cylindrical casing closed at its opposite ends by a plug and a head, a fin projecting from the exterior of the plug for earth embedment, a socket in said head and a bearing in the plug, a threaded rod rotatably extending through the head and having its lower end journaled in the plug bearing, a circumferential shoulder on the rod journaled in the head socket and locked therein against movement longitudinally thereof, a series of spaced slots in the wall of the casing, a travelling nut threaded on said rod, and a series of flukes hinged to the nut and having guide surfaces in contact with the casing to project and withdraw the flukes on longitudinal travel of the nut.

4. An expanding guy anchor comprising a sectional rod consisting of a number of units non-rotatably interlocked together, one end section having means for securing a guy wire, a tubular casing axially receiving the other end section of the rod and fixed thereto against longitudinal movement, said casing being formed with a series of spaced slots, a portion of the rod within the casing being threaded, a nut within the casing threaded on the rod, and a series of flukes hinged to the nut and moving in and out of the slots in the casing in response to movement of the nut, the backs of the flukes substantially coinciding with and closing the casing slots when the flukes are in retracted position.

LLOYD M. BLANCHARD.
